UNITED STATES PATENT OFFICE.

GEORGE W. BUGGELN, OF EAST ORANGE, NEW JERSEY.

SCARFPIN.

1,348,083.

Specification of Letters Patent.

Patented July 27, 1920.

Application filed April 23, 1920. Serial No. 376,125.

To all whom it may concern:

Be it known that I, GEORGE W. BUGGELN, a citizen of the United States, residing at East Orange, in the county of Essex and State of New Jersey, have invented certain new and useful Improvements in Scarfpins; and I do declare the following to be a full, clear, and exact description of the invention, such as will enable others skilled in the art 10 to which it appertains to make and use the same.

This invention relates to an improved scarfpin.

An object of the invention is to provide a scarf pin provided with means for embracing or surrounding the aprons of an unknotted four-in-hand necktie close up to the collar so as to give the tie the appearance of a knotted tie, thus obviating the necessity 20 of forming the knot by hand, which method is sometimes objectionable and presents many difficulties.

Another object of the invention is to provide a scarf pin of the above mentioned type 25 wherein the knot-forming-means also serves as a means for preventing possible loss of the pin.

A further object of the invention is to provide a scarf pin which may be worn with 30 a scarf whether it is tied or not, it serving to improve the appearance of the tie to a great extent.

Other objects and advantages of the invention will be apparent during the course 35 of the following description.

In the accompanying drawings forming a part of the specification and in which like numerals are employed to designate like parts throughout the same:

40 Figure 1 is a perspective view of a collar and tie, showing the manner in which my improved pin is employed.

Fig. 2 is a bottom plan view of Fig. 1.

Fig. 3 is a detail perspective view of a 45 scarf pin constructed in accordance with my invention.

Fig. 4 is a perspective view of a collar and tie showing the manner in which the latter is tied to permit application of my scarf pin 50 thereon.

In the drawings wherein for the purpose of illustration is shown a preferred embodiment of my invention, the letter C designates a collar and the letter T denotes a 55 necktie of the four-in-hand type.

As has been before intimated it is the pur-

pose of this invention to obviate the necessity of tying a four-in-hand tie in the usual way. The only step necessary to permit use of my scarf pin, is to place the tie around 60 the collar in the usual manner, and twist the aprons once in the manner shown in Fig. 4, after which the aprons will be brought together and permitted to hang in the usual manner. When in this position 65 my improved scarf pin may be readily applied and when in position, it will give the tie the same appearance as if it were tied by hand in the usual manner.

The pin for accomplishing this feature is 70 more clearly shown in Fig. 3, wherein the numeral 1 designates the scarf pin proper which has its upper end directed laterally forward as at 2, it being provided on the extreme of this bent end with an ornamental 75 head 3 of any suitable design. So far, the construction of this pin is like that of pins now in use. Extending laterally in opposite directions from the portion 2 are arms 4, each of which is directed rearwardly at 5, 80 and inwardly toward each other at 6 to form an open ring-like member which is adapted to surround the aprons of the tie close up to the collar in the manner shown in Figs. 1 and 2. This ring-like member forms the 85 aforesaid knot-forming means, and also prevents possible loss of the pin from the tie.

In use, the tie is placed upon the collar in the usual manner, and the free ends of the aprons are twisted around each other in the 90 manner more clearly disclosed in Fig. 4, after which they are brought together and permitted to hang down over the bosom in the manner shown in Figs. 1 and 2. When in this position, the pin 1 may be placed in 95 position in the usual way. It is to be stated here, that when placing the pin in position, the ring-like member should be rather close up to the collar so that the knot which is formed will not be too long. However, 100 the length of the knot may be determined by the user. After the pin is in position, the aprons of the tie will be forced through the space between the extremities of the arms 4. Such operation will cause the tie 105 to be gathered or contracted in the manner disclosed in Fig. 1, thus giving the tie the appearance of a knotted tie.

A pin constructed in accordance with my invention will be found extremely useful 110 and advantageous in that it will dispense with the necessity of tying the knot by hand.

It will be recalled that when tying the usual four-in-hand tie, it is necessary to slide it through the collar to properly position the knot. Sometimes the tie gets caught on the back collar-button and is torn, and at other times much difficulty is experienced in sliding the tie for positioning the knot. With my pin such circumstances will be avoided. Soiling of the tie will be prevented to a great extent. Due to the construction employed, it would be almost impossible for the pin to work itself out of the tie, and it will be also an extremely hard matter for a person to steal the pin from the tie, because it cannot be removed by one hand, thus, the necessity of employing a safety catch is dispensed with. Also, use of my pin will enable the knot to be made of any desirable size. Then again, the pin may be used with hand tied scarfs if desired, and it will serve as an extremely attractive ornament, thus increasing the appearance of the tie.

A careful consideration of the foregoing description taken in connection with the accompanying drawings will enable persons skilled in the art to which this invention appertains to obtain a thorough understanding of the same, therefore, further description is deemed unnecessary.

It is to be understood that the form of my invention herein shown and described is to be taken as a preferred form of the same

and that various minor changes in the shape, size and arrangement of parts may be resorted to without departing from the spirit of the invention or the scope of the subjoined claims.

What is claimed is:

1. An article of the type set forth comprising a split ring-like band adapted to surround a necktie, and a scarf pin carried by the band, said pin being secured to the band intermediate the ends of the latter and including an inwardly extending portion which extends into the band and a portion which is directed downwardly and at right angles to said inwardly extending portion. 40 45

2. An article of the class described comprising a scarf pin provided with a pair of laterally disposed arms extending in opposite directions and being directed rearward and then toward each other, being adapted to embrace a necktie. 50

3. An article of the class described comprising a scarf pin having its upper end bent forwardly, an ornamental head on the extremity of the forwardly bent end, and a pair of arms extending laterally in opposite directions from the bent end of the pin, 60 being then directed rearwardly and toward each other, thus forming a member which is adapted to embrace a necktie. 55

In testimony whereof I have hereunto set my hand.

GEORGE W. BUGGELN.
